Primary Examiner — Janice Patyk*Assistant Examiner* — Ji Sun Yoon(74) *Attorney, Agent, or Firm* — Tutunjian & Bitetto, P.C.(57) **CLAIM**

The ornamental design for a bottle as shown and described.

DESCRIPTION

FIG. 1 is a top perspective view of a bottle showing my new design;

FIG. 2 is a front view thereof;

FIG. 3 is a right side view thereof;

FIG. 4 is rear view thereof;

FIG. 5 is a left side view thereof;

FIG. 6 is a top view thereof; and,

FIG. 7 is a bottom view thereof.

The broken lines in the figures illustrate portions of the bottle that form no part of the claimed design.

The sidewall of the bottle has been shown with symbolic breaks. The appearance of any portion of the article between the break lines forms no part of the claimed design.

1 Claim, 7 Drawing Sheets(56)
